UNITED STATES PATENT OFFICE.

ALFRED P. MORAN, OF NEW YORK, N. Y.

DESIGN FOR A SEWER-TRAP.

SPECIFICATION forming part of Design No. 32,108, dated January 16, 1900.

Application filed December 11, 1899. Serial No. 740,010. Term of patent 14 years.

To all whom it may concern:

Be it known that I, ALFRED P. MORAN, a citizen of the United States, and a resident of the city of New York, borough of Manhattan, in the county and State of New York, have invented and produced a new and original Design for a Sewer-Trap, of which the following is a full, clear, and exact description.

Reference is to be had to the accompanying drawings, forming a part of this specification, in which similar characters of reference indicate corresponding parts both the views.

Figure 1 is a side elevation of a sewer-trap, showing my design; and Fig. 2 is a transverse section of the same on the line 2-2 in Fig. 1.

The leading feature of my design consists in the design forming the subject-matter of the accompanying illustration.

The design in its entirety consists of a U-shaped tubular body A, terminating at its ends in horizontally-disposed tubular ends B and C, extending in opposite directions relatively to each other, tubular offsets D D' appearing at the top of the junction of the

body A with the said ends B and C, respectively, the said offsets D D' standing at obtuse angles to the ends B and C, respectively, and appearing with necks E, flaring outwardly at their bottom portions to gradually merge in 30 the walls of the body A and the ends B and C, the space between the wings of the body A being formed in a V-like shape, with its upper end curved slightly inward or contracted to merge with the inner or adjacent 35 side of the offsets D and D' and to combine therewith in producing the outlines of a figure simulating an arrow-head.

Having thus fully described my invention, I claim as new and desire to secure by Letters 40 Patent—

The design for a sewer-trap, as herein shown and described.

In testimony whereof I have signed my name to this specification in the presence of 45 two subscribing witnesses.

ALFRED P. MORAN.
